UNITED STATES PATENT OFFICE

WILLIAM A. BLAHUT, OF MALDEN, MISSOURI

ICE-CUTTING MACHINE

Application filed June 20, 1928. Serial No. 287,009.

This invention relates to an ice cutting device and has for its primary object the provision of an instrument which can be employed to quickly and accurately cut a block 5 of ice along any desired line.

Another object of the invention is the provision, in a manner as hereinafter set forth, of a device which, when used upon the usual block of manufactured ice, can be employed 10 to cut a piece of desired weight.

A still further object of the present invention is to provide an ice cutting device which will perform the cutting operation with a minimum of wastage through the formation 15 of chips.

The invention will be best understood from a consideration of the following detailed description taken in connection with the accompanying drawings forming a part of the present invention, with the understanding, however, that the invention is not confined to any strict conformity with the showing of the drawings but may be changed or modified, so long as such changes or modifications mark 20 no material departure from the salient features of the invention as expressed in the appended claim.

In the drawings:

Figure 1 shows the instrument embodying 30 the present invention, in side elevation, the position of a block of ice being indicated in dotted lines.

Figure 2 is an elevational view of the device looking at the same from a side opposite that 35 shown in Fig. 1.

Figure 3 shows the device in edge elevation.

Figure 4 is a top plan view of the device.

Figure 5 is a sectional view taken upon the 40 line 5-5 of Figure 3.

Figure 6 is a transverse section taken upon the line 6-6 of Figure 4.

Figure 7 is a view in detail showing the manner in which the pick spikes are mounted 45 in the jaw arm.

Referring now to the drawings in detail wherein like numerals of reference indicate corresponding parts throughout the several views, it will be seen that the present structure comprises two main elements of substan-

tially L-shaped configuration, these elements being indicated by the numerals 1 and 2. Each of the elements or frames 1 and 2 comprises a relatively long jaw arm, the jaw arm of the element 1 being indicated by the numeral 3 and that of the element 2 being indicated by the numeral 4. The arms 3 and 4 at one end have the right angularly extended angled bars 5 and 6 respectively which, when the structure is set up, are arranged 55 to extend in opposite directions in side by side contacting relation as shown in Figures 5 and 6.

Each of the jaw arms 3 and 4 carries upon its inner edge a plurality of longitudinally extending picks or spikes 7, these spikes being positioned in opposed relation when the jaw arms are in operative position. The arms are each provided at the inner end of each spike 7 with a transversely extending aperture 8 into which a suitable tool may be inserted to wedge behind the spike end which extends thereinto, for forcing the spike outwardly when it is desired to remove the same. 65

The angle 5 has its top edge formed to provide a series of teeth 9 thus forming the angle 5 into a rack bar. 70

The angle 6 has formed intermediate its ends the upstanding gear 7 which is transversely apertured to make a bearing of the 75 same. 80

When the angles 5 and 6 have been placed in the side by side relation shown in Figure 5 there is arranged thereover the longitudinally extending channelled casing which is indicated as a whole by the numeral 11, this casing constituting a back portion 12, a top plate 13, and a bottom plate 14, the top plate 13 being provided intermediate its ends with a recess 15 for the reception of the ear 10 on the angle 6, the angle 5 being arranged between the angle 6 and the back plate 12 of the casing. 85

At the inner end of the recess 15 there is formed an upstanding apertured bearing ear 16, which is, of course, directly opposite the bearing ear 10 which is carried by the angle 6. 90

A shaft 17 is passed through the bearing ears 10 and 16 and mounted upon this shaft between the ears is a gear 18 which meshes with the teeth of the angle bar 5. Each end 100

of the shaft 17 which extends beyond its adjacent supporting bearing, carries the crank member 19, these crank members extending in opposite directions and being suitably secured to the shaft as for example by means of the pins 20 or other appropriate devices.

Suspended from the shaft 17, adjacent each end thereof, and between a crank and ear, is a bracket arm 21 that arm which passes over the rack plate 12 of the casing 11 being secured to the casing as shown in Figure 1. These brackets 21 extend downwardly a substantial distance and in spaced parallel relation as shown, and attach at their lower free ends to a block 22 which is secured to or forms a part of a gage bar 23, the block being positioned midway between the ends of the gage bar as shown in Figure 3.

As is also shown the bar 23 extends at right angles to the sides of the jaw arms 3 and 4, and when the structure is placed in position with the arms adjacent opposite faces of the block of ice with the gage bar resting upon the upper surface of the block with one end flush with the adjacent end of the ice block, the length of the gage bar is such as to so position the jaw arms so that when the same are brought together in the manner hereinafter described, a section of ice will be removed equivalent to one third the entire weight of the block, or in other words there will be removed a block of ice weighing fifty pounds. It is of course understood that when the device is used for removing fifty pound pieces of ice from a block which normally weighs one hundred and fifty pounds the block is laid upon one longitudinal edge with the gage bar resting upon and extending lengthwise of the opposite or upper longitudinal edge thus making the cut transversely of the block. It will be obvious that further cuts can be made in a similar manner to divide the piece into twenty-five and twelve and one half pound sections.

From the description of the structure of the present ice cutting device it is believed that the operation of the same will be obvious, for, when the jaw arms are arranged upon opposite sides or against opposite faces of an ice block and the crank members 19 actuated to rotate the pinion gear 18 it will be readily seen that the bar 5 will be moved longitudinally of the adjacent bar 6 thus bringing the jaw arms 3 and 4 together forcing the spikes 7 into the adjacent faces of the body of ice.

This action causes the ice block to split in a straight transverse line with a minimum of chipping.

Having thus described my invention, what I claim is:

An ice cutting machine comprising a pair of substantially L-shaped members each having a long arm and a short arm and having the short arms arranged in abutting parallel relation, a casing receiving said short arms

and having a recess in the top thereof, gear teeth formed upon the top edge of one of said arms, a shaft extending transversely of the casing, a gear on said shaft to extend through the aperture for engagement with said gear teeth, means for rotating the shaft, a plurality of ice penetrating picks carried by and projecting from the opposed faces of the long arms, bracket arms depending from the shaft on opposite sides of the casing, and a gage bar secured to the bracket arms and extending beneath and transversely of said short arms for determining the position of the cutting machine upon an ice block to cut a block of desired size.

In testimony whereof I affix my signature.

WILLIAM A. BLAHUT.
